UNITED STATES PATENT OFFICE.

WALTER A. JOHNSON AND RUDOLF HUECKLER, OF THREE RIVERS, MICHIGAN.

TESTING MACHINE.

Application filed August 14, 1925. Serial No. 50,252.

This invention relates to testing machines for ascertaining the bursting strength of sheet materials such as paper and cloth and the like, and it consists of the matters hereinafter described and more particularly pointed out in the appended claims.

The primary object of the invention is to provide a machine for accurately ascertaining the bursting strength of various kinds of paper, and one which includes a resistance member that remains constant and invariable and unaffected by climatic or temperature changes.

A further object of the invention is to provide a machine which is of simple, yet strong and rigid construction, and one which is easy to manipulate for its intended purpose.

These objects of the invention as well as others, together with the many advantages thereof will more fully appear as we proceed with our specification.

In the drawings:—

Fig. 1 is a view in front elevation of a testing machine embodying our invention.

Fig. 2 is a longitudinal vertical section through the machine, on an enlarged scale, the plane of the section being indicated by the line 2—2 of Fig. 3.

Fig. 3 is a transverse vertical sectional view as taken on the line 3—3 of Fig. 2.

Fig. 4 is a perspective view of a forked post embodied in our improved testing machine.

Fig. 5 is a perspective view of a plunger forming a part of our improved testing machine.

Fig. 6 is a detail view partly in elevation and partly in section of the connection between the resistance device and plunger of our improved machine and will be referred to in more detail later.

Fig. 7 is a detail view on an enlarged scale of the brake actuating mechanism for the resistance member.

Fig. 8 is a transverse vertical sectional view as taken on the line 8—8 of Fig. 6.

Fig. 9 is a detail view on an enlarged scale of parts shown in lower right hand corner of Fig. 2.

Referring now in detail to that embodiment of the invention illustrated in the accompanying drawings, 1 indicates as a whole an open bottom, substantially rectangular casing of a width greater than its depth. Said casing comprises upright front and rear walls 2 and 3, respectively, and up-

right side walls 4 and 5 and a top wall 6 which may be any desired shape or contour.

7 indicates a vertically movable non-rotative screw threaded post located adjacent the side wall 5 of the casing. The bottom end of said post engages in a bevelled pinion 8 which is suitably journaled in a bearing sleeve 9 forming a part of a bracket 10 fixed to and extending inwardly from the adjacent side wall 5. Said pinion meshes with a similar pinion 11 fixed on the inner end of a stub shaft 12 journaled in a bearing bushing and sleeve 13 carried by the side wall 5. On that end of said shaft without the casing is fixed a hand wheel 14 having a handle 15 by means of which it is rotated. It is apparent that when the hand wheel is turned a vertical movement will be imparted to the post through the mechanism just described.

The top end of the post 7 is formed to provide a pair of laterally disposed upright arms 16—16 each of which extends up through antifriction bearings 17 in the top wall of the casing and on the top ends of said arms is mounted a paper holder in the form of a clamping device 18 in which the paper or other material to be tested for the bursting strength is secured. Said clamping device includes a horizontally disposed plate 19 which engages upon and is fixed to the extreme top ends of the arms 16 and in said plate in line with the post 7 is an opening 20. Said plate includes a goose neck arm 21 which terminates in a vertically disposed sleeve 22 in axial alignment with the opening 20 and journaled in said sleeve is a plunger 23. The bottom end of said plunger carries an inverted cup-like clamping member 24 and the top end of said plunger which is reduced in diameter extends through the top end of said sleeve. A helical coiled compression spring 25 surrounds said reduced part of the plunger within the sleeve and normally urges said plunger and member into engagement with the plate 19. In the bottom of said cup-like member 24 is a recess 26 in line with the opening 20. The extreme top end of said plunger carries a cross pin 27 under which the short arm 28 of a lever 29 extends, said lever being pivoted at 30 on the goose neck arm 21. The piece of paper 31 to be tested (see Fig. 1) may be inserted into the space between the plate 19 and member 24 after depressing the lever 29. After releasing the pressure on said lever, the member 24 will act (through

the spring 25) to securely clamp the material to be tested in place.

In vertical alignment with the post 7 and the opening 20 in the clamping plate a plunger is provided, which plunger includes a cylindrical top portion 31 and a bottom forked portion having laterally spaced arms 32, as best shown in Fig. 5. Said cylindrical portion of the plunger slides through an antifriction bearing 33 formed in the top wall of the casing and the extreme top end of said cylindrical portion which is formed to eliminate sharp corners is normally located just below the clamping plate 19. The bottom ends of the fork arms 32 are normally adjacent the top end of the post 7 proper with which it is in alignment and to said bottom ends of said arms is attached one end of a link or sprocket chain 34. Said chain which is relatively short is trained over the segmental head 35 of a constant and invariable resistance member 36 and the other end of said chain is fixed to said head as at 37, said head having side flanges 38 to prevent lateral displacement of said chain. The resistance member is a dead weight and consequently is unaffected by temperature or climatic changes and is in the form of a normally depending segmental body 39 of a radius much greater than that of the head 35. The said member normally hangs pendent while in its inoperative position and includes an extension 39^a which projects underneath the bearing bracket 10. Said resistance or dead weight member 36 is fixed on a short horizontal shaft 40 suitably journaled in antifriction bearings 41-41 fixed in lugs 42 projecting inwardly from the front and rear walls 2 and 3 of the casing 1 as best shown in Fig. 8. The body 39 of said resistance member, carries on that side adjacent the front wall 2, an arcuate rack 43 with which meshes a pinion 44 on a forwardly extending shaft 45 journaled in said front wall. On said front wall is a gage 46 suitably calibrated in the desired units or graduations of measurements in the manner well known and fixed on said shaft 45 is a hand or pointer 47 cooperating with the calibrations of the gage. In the operation of the machine the clamping plate 19 with the paper thereon is moved downwardly under the action of turning the handwheel 14 in one direction, until the paper engages the rounded top end of the cylindrical portion 31 of the plunger which will then move downwardly with the clamping plate. In this movement, the body 39 of the resistance member 36 will swing clockwise, imposing a resistance to the action of the downward movement of the plunger in proportion to the amount of swinging movement of the resistance member. In the movement of said resistance member body, the rack 43 will rotate the

shaft 45 and indicator hand to visibly present to view the amount of resistance imposed on the paper, which resistance is, of course, increased as the weight is swung clockwise. When the paper can no longer withstand the increasing weight, the plunger will break through the paper, which paper is at the limit of its resistance to a bursting pressure, which pressure is registered or indicated on the gage. When the plunger breaks through the paper, the rounded top end thereof enters the recess 26 in the clamping member 24.

Means are provided to prevent the return swing of the resistance member 39 when the plunger breaks through the paper and said means are as follows:—50 indicates ratchet toothed bar located between the resistance member 36 and the front wall of the casing and made on an arc concentric with the shaft 40. Said toothed bar is pivoted at one end to a cross shaft 51 fixed in the front and rear walls 1 and 2 near the junction of the end wall 4 and top wall 6. The other end of said toothed bar is supported for a slight swinging movement by means of a link 52, one end of which is pivotally connected to said end of said bar and the other end of which is pivotally connected to the free end of a short arm 53 fixed on a transverse horizontal rock shaft 54 journaled at its ends in the front and rear walls of the casing. Said shaft has secured to that end thereof without the front wall 2, a lever arm 55 by which it is manipulated, and secured to said shaft within the casing, adjacent the arm 53, is a segmental plate 56, the purpose of which will appear later. On that side of the resistance member or dead weight adjacent the plane of the toothed bar 50 and near the periphery thereof is provided a dog 57 which in the swinging movement of the dead weight in one direction will drag over the teeth of said bar and when the plunger breaks through the paper, will act to hold said dead weight against a return movement under gravity so that the amount of resistance on the paper will be registered by the gage for the purpose of observation. As it is impractical to make the teeth of the rack bar too fine, we provide a plurality of such pawls having ends slightly offset from one another, any one of which will act in conjunction with the engaged tooth to hold the dead weight as is apparent. Said pawls are urged into engagement with said rack bars by means of a weight member 58 to eliminate the use of springs therein.

To permit the slow, easy return of the dead weight or resistance member to its normally inactive position instead of a quick swing, after releasing the bar 50 from the pawl 57, we provide a braking shoe with which the peripheral part of said resistance

member has wiping or braking contact when moving toward its normal inoperative position, but which is out of engagement with said member when in its operative swinging 5 movement.

Said means includes an arcuate brake shoe 60 which is made substantially concentric with the axis of the deadweight or resistance member shaft 40 and which is also pivoted 10 at one end on the shaft 51 before mentioned. The other end of said brake shoe normally rests on a cam-like member 61 fixed on a horizontal rock shaft 62 parallel with the rock shaft 54, and located between said shaft 15 and the side wall 5. Said shaft 62 is journaled at its ends in the front and rear walls of the casing. Secured to said shaft 62 within the casing and near said front and rear walls 2 and 3 are rearwardly extending 20 arms 63, the free ends of each of which are pivotally connected to the bottom end of an associated upright link 64. The top end of each link is operatively connected to an extension arm 65, one fixed to each of the 25 yoke arms 16. On the shaft 62 between the plate 56 on the shaft 54 and the front wall of the casing is a segmental ratchet wheel 66 with which a pawl 67 pivoted on said 30 plate engages to hold the shaft 62 against a reverse movement until released. When in the operation of the machine the post 7 and arms 16 are moved downwardly, the shaft 62 is turned a partial revolution to cause the 35 cam 61 to lift the free end of the brake shoe upwardly as the resistance member is swinging clockwise so as to bring the brake shoe into position to be engaged by the resistance member in its counter clockwise movement, after a test has been made and it is desired 40 to restore the parts to their normal positions. In the movement of the rock shaft 62, the pawl 67 will click over the teeth of the ratchet 66 and will hold the rock shaft against reverse movement as before described. 45

After a test has been made and the bursting strength of the paper being tested has been disclosed by the gage, the operator swings the lever 55 upwardly and rocks the 50 shaft 54 which through the arm 53 and link 52 swings the free end of the rack bar downwardly so as to release it from the pawl 57. In the upward swinging movement of the lever 55 the plate 56 carrying the pawl 67 55 moves away from the ratchet 66, thus releasing the same so that after the deadweight has been released from the rack bar it will swing to its normal position and in this swing will engage the brake shoe and be retarded thereby so that the return is 60 slow and easy. Thus, no shock or jar can be imparted to the machine in the return movement of the dead weight. The hand wheel 14 is then turned in the other direction to return the post and clamping plates 65

to their normal elevated position and as the post 7 moves upwardly, the cam 61 which supports the free end of the brake shoe is moved by means of the links 64 to permit the brake shoe to return to its normal position 70 after which the lever 55 is actuated to bring the rack bar to its normal position. After removing the tested paper from the holder 18, a new piece may be inserted with all parts in a position ready for another test. 75

Our improved machine is in no manner affected in its operation by temperature or climatic changes because the resistance member is a dead weight and unaffected by such changes. The bursting strength of the 80 paper being tested is visibly presented to view by the gage and is readily readable. The brake shoe prevents such a quick return of the resistance device as would cause shocks, jars, or breakage to the associated 85 mechanisms. The parts are strong and rugged and are easily assembled in place.

While in describing our invention we have referred to certain details of mechanical construction as well as form and arrangement 90 of parts thereof, we do not wish to be limited thereto except as may be pointed out in the appended claims.

We claim as our invention:

1. A machine of the kind described embodying therein, paper holding means, a movable constant resistance member, a plunger operatively connected to said resistance member for imparting movement thereto and against which the paper is moved by said holding means, an indicator device associated with said resistance member, and means for releasably holding said resistance member upon the breaking of the plunger through the paper. 95

2. A machine of the kind described embodying therein, paper holding means, a swingable constant resistance member, a plunger operatively connected to said resistance member for imparting a swinging 100 movement thereto in one direction and against which the paper is moved by said holding means, an indicator device associated with said swingable resistance member, and means for releasably holding said resistance member in that position into which it has been swung by the plunger, upon the breaking of the plunger through the paper. 110

3. A machine of the kind described embodying therein, paper holding means, a swingable constant resistance member, a plunger operatively connected to said resistance member for imparting a swinging 115 movement thereto in one direction and against which the paper is moved by said holding means, an indicator device associated with said swingable resistance member, a pawl carried by said resistance member, and a toothed bar adapted to be en- 120

gaged thereby for releasably holding said resistance member in that position into which it has been swung by the plunger upon the breaking of the plunger through the paper.

4. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, and cooperating pawl and ratchet members, one of which is carried by said resistance member for releasably holding said resistance member in that position into which it has been swung by said plunger upon breaking of the plunger through the paper.

5. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, a pawl carried by said resistance member, a toothed bar adapted to be engaged thereby for holding said resistance member in that position into which it has been swung by the plunger upon breaking of the plunger through the paper, and means for moving the toothed bar out of engagement with the pawl on said resistance member.

6. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, means for releasably holding said resistance member in that position into which it has been swung by the plunger, upon the breaking of the plunger through the paper, and means for retarding the return movement of said resistance member after said holding means has been released.

55 7. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, means for releasably holding said resistance member in that position into which

it has been swung by the plunger, upon the breaking of the plunger through the paper, and means for frictionally engaging said resistance member for braking the return movement of said resistance member after 70 said holding means has been released.

8. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, means for releasably holding said resistance member in that position into which it has been swung by the plunger, upon the breaking of the plunger through the paper, a brake shoe normally out of engagement 80 with said resistance member when said member is swung in one direction, and means for moving said brake shoe into position to be engaged by said resistance member in its return movement after said holding means 85 has been released.

9. A machine of the kind described embodying therein, paper holding means, a swingable constant resistance member, a plunger operatively connected to said resistance member for imparting a swinging movement thereto in one direction and against which the paper is moved by said holding means, an indicator device associated with said swingable resistance member, means for releasably holding said resistance member in that position into which it has been swung by the plunger, upon the breaking of the plunger through the paper, a brake shoe normally out of engagement 95 with said resistance member when said member is swung in one direction, and means actuated by said paper holder for moving said brake shoe into position to be engaged by said resistance member upon its return movement after said holding means has been released.

10. A machine of the kind described embodying therein, paper holding means, a swingable constant resistance member, a plunger operatively connected to said resistance member for imparting a swinging movement thereto in one direction and against which the paper is moved by said holding means, a pawl carried by said resistance member, a ratchet toothed bar pivoted at one end and adapted to be engaged by the pawl for holding the resistance member in that position into which it has been swung upon breaking of the plunger through the paper, a brake shoe normally out of engagement with said resistance member when swinging in one direction, means connecting said paper holding means with said brake shoe for moving the same into position 110 115 120 125 130

- tion to be engaged by said resistance member in its return movement, said last mentioned means including a rock shaft and cam for engaging the brake shoe, and means operatively connected to the other end of the rack bar for releasing it from the pawl to permit said resistance member to swing in the other direction but in engagement with said brake shoe.
11. A machine of the kind described embodying therein, a casing, a vertically movable paper holder, a weight member swingably mounted in the casing, a plunger in said casing operatively connected to said weight member for imparting a swinging movement thereto in one direction and against which the paper is moved by said holding means, an indicator device without the casing and connected to said weight member, means actuated from without the casing for imparting movement to said paper holder and including a threaded post and gearing for imparting a longitudinal movement thereto, a pawl carried by the weight member, a toothed bar within the casing adapted to be releasably engaged by said pawl and means without the casing for causing a relative release movement between said pawl and bar.
12. A machine of the kind described embodying therein, a casing, a threaded post arranged in the casing and having laterally spaced arms projecting through the top wall of said casing, a paper holder carried by said arms, means operative from without the casing and including a gear engaged with said post for imparting a vertical movement thereto, a plunger in alignment with said post and against which the paper is moved by said holding means, a weight member pivoted in the casing for swinging movement, an indicator without the casing actuated by said weight, means connecting said weight to said plunger, a pawl carried by said weight member, a ratchet toothed
- bar in said casing adapted to be engaged by said pawl to hold said weight member in that position into which it has been swung upon breaking of the plunger through the paper, and means operable from without the casing for causing a relative release movement between said pawl and toothed bar.
13. A machine of the kind described embodying therein a casing, a swinging weight member therein, a plunger operatively connected to said weight member, a paper holder, without the casing, said plunger and paper holder being relatively movable, means releasably holding said weight member in the position into which it has been swung by said plunger upon breaking of the plunger through the paper, an indicator without the casing actuated by said weight member and means for releasing said holding means.
14. A machine for testing the bursting strength of paper for a given area including means for holding said area of paper, a dead weight member movable through the agency of the paper until it is broken by the resistance of said member, and means for visibly presenting the amount of resistance imposed on the paper at the time of its breaking through.
15. A machine for testing the bursting strength of a given area of paper, including means for holding said area of paper, a dead weight member, said holding means and dead weight being relatively movable through the agency of said area of paper until said area is broken through by the resistance of said dead weight member, and means for visibly presenting the amount of said resistance upon the breaking through of said paper area.

In testimony whereof, we have hereunto set our hands this 7 day of August, 1925.

WALTER A. JOHNSON.
RUDOLF HUECKLER.
